UNITED STATES PATENT OFFICE

169,310

TOY ANIMAL

Florence F. Fullerton, Long Island City, N. Y.

Application November 16, 1951, Serial No. 17,439

Term of patent 3½ years

(Cl. D34—2)

To all whom it may concern:

Be it known that I, Florence F. Fullerton, a citizen of the United States, residing at Long Island City, N. Y., have invented a new, original, and ornamental Design for a Toy Animal, of which the following is a specification, reference being had to the accompanying drawing, forming part thereof, in which:

Fig. 1 is a top plan view of the toy animal showing my new design;

Fig. 2 is a side view of the same;

Fig. 3 is a front view of the same; and

Fig. 4 is a bottom plan view of the same.

I claim:

The ornamental design for a toy animal, as shown.

FLORENCE F. FULLERTON.
